UNITED STATES PATENT OFFICE.

CHAUNCEY B. HAYWARD, OF WEST ORANGE, NEW JERSEY.

CLOTHES-LINE HOLDER.

1,149,757.

Specification of Letters Patent.

Patented Aug. 10, 1915.

Application filed October 25, 1913. Serial No. 797,246.

To all whom it may concern:

Be it known that I, CHAUNCEY B. HAYWARD, a citizen of the United States, and a resident of West Orange, in the county of 5 Essex, in the State of New Jersey, have invented certain new and useful Improvements in Clothes-Line Holders, of which the following is a specification.

My invention relates to clothes line holders to be used in connection with endless or pulley clothes lines, for connecting the lower and upper bights of the line to prevent undue sagging of the lower line to which the clothes are attached, and which supports the 15 weight of the wet clothes.

The upper and lower bights of a clothes line, when the clothes are in place on the lower bight and the same is connected to the upper bight, in the regions where the two 20 bights are connected together, naturally fall into reverse curves; that is to say the upper bight is drawn down at the point of attachment, and curves upwardly away therefrom on either side, whereas the lower bight, being 25 supported at the point of connection, falls away therefrom on either side, the amount of sag and the precise curves assumed by the two bights of the line being dependent upon the location in the line of the 30 connecting means, the amount of tension to which the line is subjected, and the weight of the objects supported by the line.

A holder constructed in accordance with my invention is formed with reference to 35 these conditions, being made up of a single preferably integral block of any desirable material, preferably glass or porcelain, or similar vitreous moldable material, and is provided with passages therethrough, which 40 passages are curved in reverse direction, so as to conform to the natural curves of the two bights of the clothes line, thus permitting the line to pass therethrough without the necessity of pulleys or other similar devices which are likely to tear the clothes, 45 catch and bind, as when the line gets into the space between the pulley and its support, and to get out of order in various ways.

A holder according to my invention being 50 made of substantial length, so that the passages formed therein are likewise of substantial length, will not catch or bind on the line in the manner familiar in the case of fasteners for tent ropes and the like, which 55 are formed with short passages and are held in place by being pulled to one side, creating

reverse bends or a kink in the rope, which prevents their sliding thereon.

A clothes line holder constructed in accordance with my invention is extremely 60 cheap, is capable of being made of substantially indestructible material, and will therefore last for a long time and will not soil or injure the clothes or the clothes line and will not catch or bind line in use. 65

Other advantages and objects of my invention will appear hereinafter in connection with the description thereof, and with the foregoing and related objects in view, my invention consists in the parts, improvements and combinations herein set forth and claimed. 70

In the drawings forming a part of this specification, and wherein the same reference numerals are used to designate the same 75 parts throughout, Figure 1 is a view showing a holder in accordance with my invention in place on a clothes line, Fig. 2 is an end view of the holder, and Fig. 3 a side view thereof. 80

Reference numeral 1 is used to indicate the holder generally and the reverse curved passages therein which are preferably formed in the molding of the holder, are indicated by the numerals 2, 2. These passages are 85 preferably circular in cross section and of a diameter substantially twice the diameter of the clothes line with which the holder is to be used, or thereabouts, and the inner walls thereof are made as smooth as possible 90 so that the line may pass through these passages without any considerable amount of friction or wear. Block 1 may be made thinner at the middle as shown in Fig. 2 at 95 3, 3 in order to make it lighter without unnecessary loss of strength, and its edges may be curved inwardly as shown at 4, 4, Fig. 3, in lines generally parallel to the curved passages 2, 2, thus improving the appearance of the article and making it easier to 100 hold with wet hands, an important consideration to the washerwoman hanging out the clothes whose hands are substantially always wet while this operation is being performed. 105

Beads 5 are preferably formed at the junction of the inner wall of block 1 with the sides and edges thereof to prevent chipping, and to do away with objectionably sharp corners. 110

In order to make use of a holder in accordance with my invention, the lower and

upper bights of the clothes line are passed through the openings 2, 2 respectively, the holder being preferably arranged initially just behind the knot or other means whereby the ends of the rope are secured together, such knot or other enlargement being formed in the lower bight of the line just ahead of the holder, so that as the line is pulled out the knot or other fastening will 10 travel away from the pulley or other support over which the rope is passed at the operator's station. If the line is sufficiently long to require a number of holders, they are initially strung along behind one another with the knot or other fastening ahead of the first one, as described above.

When the upper support of the rope is higher than that at the operator's station, as is usually the case, the line passes easily 20 through the openings 2 and will not move the holder, but it will remain under the influence of gravity in the neighborhood of the pulley or other support at the operator's station. If the outer support is as low or 25 lower than that at which the operator is stationed, the holder can be kept back so not to interfere with the securing of the clothes to the line by a mere push of the operator's hand without the necessity of any precautions being exercised to keep it straight or 30 in any given relation to the line.

When a sufficient quantity of clothes have been hung on the line to require that the lower bight be supported from the upper bight, the holder is pushed out, and the subsequent additions to the clothes on the line are fastened behind it, and if it requires to be supported from the upper bight at more than one point, a plurality of holders initially placed on the line behind one another, as already described, are advanced one by one, and brought into use as required. The holder or holders may be readily advanced on the upper bight of the rope as 40 the curved passage 2 within which the rope is received conforms substantially to the curve in the upper bight of the line, and very little friction is set up between the line 45

and smooth inner wall of passage 2, which substantially conforms to the natural curve 50 of the line, so that the holder moves freely without likelihood or tendency to binding, and the remaining passage 2 conforming to the natural curve of the lower bight of the rope, no twisting stresses are set up to interfere with the free passage of the upper bight of the rope through the upper passage 55 2. If after very long use there at any time should be too great wear on the block within the upper passage where it moves 60 on the upper bight of the line, as when a comparatively soft material is used for constructing the holder, the upper and lower halves being substantially identical, it will be readily possible to reverse the position 65 of the holder, thus bringing a comparatively unworn surface to the region of greatest wear.

It is to be understood that changes may be made in the construction shown within 70 the scope of my claims without departing from my invention, or sacrificing any of the advantages thereof.

Having now described my invention, I 75 claim:

1. In a clothes line holder, a block of substantial length and made of one piece, the block having curved passages, the passages being curved in the same plane, said passages also having their ends arranged so 80 that they diverge where they emerge from the block, substantially as set forth.

2. A clothes line holder comprising a block of substantial length having two reversely curved passages extending through 85 it, the passages being smooth and large enough to permit a line to pass freely through them, substantially as set forth.

In witness whereof I have signed my name to this specification, this 23rd day of 90 October, 1913, in the presence of two subscribing witnesses.

CHAUNCEY B. HAYWARD.
